UNITED STATES PATENT OFFICE.

EDWARD B. VANDERGAW, OF BROOKLYN, AND JULES HEINRICH, OF NEW YORK, N. Y.,
ASSIGNORS TO FRED BUTTERFIELD & CO. INC., OF NEW YORK, N. Y., A CORPOR-
ATION OF NEW YORK.

DESIGN FOR FLOCKED VOILE FABRIC.

Application filed August 30, 1924. Serial No. 10,620. Term of patent 3½ years.

To all whom it may concern:

Be it known that we, EDWARD B. VANDER-
GAW and JULES HEINRICH, citizens of the
United States, residing, respectively, in the
boroughs of Brooklyn and Manhattan, in
the city and State of New York, have jointly
invented a new, original, and ornamental
Design for Flocked Voile Fabric, of which
the following is a specification, reference

being had to the accompanying drawing,
forming part hereof.

The figure is a plan view of a piece of
flocked voile fabric showing our new design.

We claim:

The ornamental design for flocked voile
fabric, as shown.

EDWARD B. VANDERGAW.
JULES HEINRICH.
